JACQUARD

Joseph Ashworth and Albert Firth, Bradford, England, assignors to John T. Hardaker, Limited, Bradford, England, a British company

Application March 27, 1952, Serial No. 278,942

11 Claims. (Cl. 139—329)

1

This invention relates to double lift double cylinder jacquards and especially to the driving and mounting means for the two jacquard cylinders.

Difficulty is often experienced in jacquards of this type in constructing the main power drive to the jacquard cylinders due to the fact that initially accurate setting is required, and furthermore, after a given life, it is often found that there is not true engagement between the driving element and the stage by stage driven element operating each cylinder.

The main object of the present invention is to provide a double lift double cylinder jacquard including a pair of rotatable jacquard cylinders, including a substantially central main driving shaft, a pair of shafts driven from said main shaft, said driven shafts being changeable in their position and effective length to allow adjustment of driving and mounting units between said driven shafts and the jacquard cylinders.

Another object is to provide a double lift double cylinder jacquard including a pair of rotatable jacquard cylinders, driving and mounting means for the two jacquard cylinders including a substantially central main driving shaft, a pair of shafts driven from said main shaft, said driven shafts being changeable in their effective position and length, and each being supported at its inner end by a carrier bracket supported on the main driving shaft, said construction of each driven shaft and its carrier bracket allowing adjustment of driving and mounting units between said driven shafts and the jacquard cylinder.

A further object is to provide a double lift double cylinder jacquard, including a pair of rotatable jacquard cylinders, driving and mounting means for the two jacquard cylinders including a substantially central main driving shaft, a pair of telescopic shafts driven from said main shaft, a carrier bracket at the inner end of each driven shaft and supported on the main driving shaft for the driven shaft to be capable of pivotal movement, a pair of bevel gears at the outer end of each driven shaft, a driving element on the driven bevel gear engaging a stage by stage driven member secured on the shaft of one of the jacquard cylinders, and an adjustable mounting for allowing relative movement between the cylinder shaft and the axis of the driven bevel gear.

Referring now to the accompanying drawings, in which an embodiment of the invention is shown:

Fig. 1 is a front elevation of a jacquard including the improved cylinder driving and mounting means;

2

Fig. 2 is a side elevation of Fig. 1;

Fig. 3 is a sectional side elevation showing a detail of the mounting for the cylinder drive unit;

Fig. 4 is a detail side view of the clutch in the main drive; and

Fig. 5 is a fragmentary plan view, on an enlarged scale, of the mounting of the driven shafts.

As shown in the drawings the jacquard 1 is generally of known construction and need not be described in detail as the invention is concerned with the main drive and mounting for the two jacquard cylinders 2. The main drive shaft 3 is furnished with a clutch comprising the movable bobbin 4 mounted with a driving bevel gear 6 on the sleeve 7 and both in driving connection therewith. The clutch bobbin 4 has two sets of clutch teeth 8, 9, so that it can be moved by a fork 10, which engages a relatively wide groove 11, either into engagement with a chain wheel 12, from which it is spring returned, or into engagement with the driven clutch part 13 secured to the main driving shaft 3. The chain wheel 12 is loose on the sleeve 7 and connected by chain 14 with the hand-operating gear 15 so that the cylinders can be rotated manually at will by the bobbin 4 being engaged with the chain wheel. Normally, in the position shown, motion is picked up from the main shaft by the driver 13 and transmitted through the clutch bobbin 4 to the sleeve 7 on which is fastened the bevel gear 6. This wheel drives a pair of bevel pinions 16 attached to the ends of the telescopic shafts 17 and housed in brackets 18 which are supported by the main shaft 3 so as to be able to pivot about same for adjustment purposes. The outer ends of these two shafts are supported by bearings 19 attached to the ends of studs 20 which can rotate therein. Each shaft is furnished with a bevel pinion 21 meshing with a driven bevel gear 22 also mounted on the stud 20, and this bevel gear is furnished with a projecting peg 23 forming a driving element for a slotted star wheel 24 secured on the cylinder shaft 25 and forming a stage by stage driving member. Each shaft 25 is supported by a cylinder bearing 26 which is adjustably secured to a cylinder bearing bracket 27 on the jacquard framework. The bearing can be adjusted by screw 28 and clamped by a bolt 29 (or bolts) after being set. The bearing 26 has the inner end of the stud 20 secured thereto and the projecting outer end of the stud 20 is eccentric to the inner end of the stud so that on rotation the bevel gear 22 will be moved relative to the star wheel 24 for causing adjustment between the latter and its driving peg 23. Thus

the cylinder, which is shown with six sides, is turned one sixth of a revolution to every revolution of the main shaft and allowance is made by the aforesaid adjustment to ensure that the peg and star wheel are properly geared together by being associated with the same bearing 26. Should any discrepancy arise due to wear, the distance between centres of the shaft 25 and bevel wheel 22 can be regulated by means of the eccentric stud 20.

It will be understood from the above that adjustment between the driving element and the stage by stage driven member can be made at will due to the fact that the shafts 17 are telescopic and pivotally carried at their inner ends relative to the main drive shaft so that an up or down movement of the outer ends of the shafts 17 can be made as required.

In the above manner the two jacquard cylinders can be power driven through the clutch and when required this power drive can be arrested and the cylinders moved, say, reversed, by hand. To accomplish this the clutch bobbin 4 is disengaged from the driver 13 and at the same time engaged with the chain wheel 12 which is normally stationary. This operation can only be brought into use when the cylinders are at half stroke due to a shroud 30 being provided on the driver 13 with two truncated V-shape notches 30a cut at appropriate positions on its perimeter and a finger 31 provided on the clutch fork 10 which serves as a safety stop and allows the clutch to be disengaged only when it is opposite one of the notches. The possibility that the loom operator may try to re-engage the clutch in such a position that it will cause damage is overcome by the provision of the relatively wide groove 11 in the clutch bobbin 4 which allows the clutch fork considerable movement even when the clutch is not properly in gear.

What we claim is:

1. A double lift double cylinder jacquard including a pair of rotatable jacquard cylinders, driving and mounting means for the two jacquard cylinders, including a substantially central main driving shaft, a pair of shafts driven from said main shaft, said driven shafts being changeable in their position and effective length to allow adjustment of driving and mounting units between said driven shafts and the jacquard cylinders.

2. A double lift double cylinder jacquard including a pair of rotatable jacquard cylinders, driving and mounting means for the two jacquard cylinders including a substantially central main driving shaft, a pair of shafts driven from said main shaft, said driven shafts being changeable in their effective position and length, and each being supported at its inner end by a carrier bracket supported on the main driving shaft, said construction of each driven shaft and its carrier bracket allowing adjustment of driving and mounting units between said driven shafts and the jacquard cylinders.

3. A double lift double cylinder jacquard, including a pair of rotatable jacquard cylinders, driving and mounting means for the two jacquard cylinders including a substantially central main driving shaft, a pair of telescopic shafts driven from said main shaft, a pair of bevel gears at the outer end of each driven shaft, and a driving element on the driven bevel gear engaging a stage by stage driven member secured on the shaft of one of the jacquard cylinders.

4. A double lift double cylinder jacquard ac-

ording to claim 3 wherein the stage by stage driven member comprises a slotted star wheel engaged by a driving element comprising a peg projecting from the driven bevel gear.

5. A double lift double cylinder jacquard, including a pair of rotatable jacquard cylinders, driving and mounting means for the two jacquard cylinders including a substantially central main driving shaft, a pair of telescopic shafts driven from said main shaft, a carrier bracket at the inner end of each driven shaft and supported on the main driving shaft for the driven shaft to be capable of pivotal movement, a pair of bevel gears at the outer end of each driven shaft, a driving element on the driven bevel gear engaging a stage by stage driven member secured on the shaft of one of the jacquard cylinders, and an adjustable mounting for allowing relative movement between the cylinder shaft and the axis of the driven bevel gear.

6. A double lift double cylinder jacquard including a pair of rotatable jacquard cylinders, driving and mounting means for the two jacquard cylinders including a substantially central main driving shaft, a pair of shafts driven from said main shaft, said driven shafts being changeable in their position and effective length to suit adjustment of driving units between said driven shafts and the jacquard cylinders, said units including a pair of bevel gears at the outer end of each driven shaft, a driving element on the drive bevel gear engaging a stage by stage driven member secured on the shaft of one of the jacquard cylinders, an adjustable mounting for allowing relative movement between cylinder shaft and the axis of the driven bevel gear, said driven bevel gear being supported on a stud having an eccentric portion and projecting from a cylinder shaft bearing, whereby the distance between the cylinder shaft axis and that of the driven bevel gear can be adjusted.

7. A double lift double cylinder jacquard according to claim 6 characterised in that said stud is carried by an adjustable bearing for the cylinder shaft, said stud being furnished with an eccentric portion supporting said driven bevel gear, and a mounting for the outer end of the driven shaft.

8. A double lift double cylinder jacquard, including a pair of rotatable jacquard cylinders, driving and mounting means for the two jacquard cylinders including a substantially central main driving shaft, a pair of shafts driven from said main shaft, said driven shafts being changeable in their position and effective length to allow adjustment of driving and mounting units between said driven shafts and the jacquard cylinders, and a clutch in the main driving shaft so that the power drive to the driven shafts can be disengaged at will.

9. A double lift double cylinder jacquard according to claim 1, characterised in that the main driving shaft is furnished with a driving bevel gear wheel in engagement with a pair of driven bevel gear pinions each secured to one of the driven shafts, said each driven shaft being supported by a carrier bracket mounted on the main driving shaft to accord pivotal movement of the driven shaft for adjustment purposes, said driven shafts extending radially away from the driving shaft axis in opposite directions and normally lying in an inclined plane.

10. A double cylinder jacquard according to claim 8, wherein the clutch movable element is furnished with a wide groove for engagement by

a clutch fork whereby considerable movement is allowed for between fork and clutch part even when the clutch is not properly in engagement, to obviate damage to the clutch parts.

11. A double lift double cylinder jacquard according to claim 8, wherein the clutch movable element is adapted to be disengageable from its co-acting clutch part in the main power drive and engageable with hand operating gear for enabling the cylinders to be rotated manually. 10

JOSEPH ASHWORTH.
ALBERT FIRTH.
